CLAIM

The ornamental design for a paring knife, as shown and described.

DESCRIPTION

FIG. 1 is a front perspective view of an embodiment of handle design for a paring knife;

FIG. 2 is a front view of the paring knife of FIG. 1;

FIG. 3 is a back view of the paring knife of FIG. 1;

FIG. 4 is a left side view of the paring knife of FIG. 1;

FIG. 5 is a right side view of the paring knife of FIG. 1;

FIG. 6 is a top view of the paring knife of FIG. 1; and,

FIG. 7 is a bottom view of the paring knife of FIG. 1.

The broken line shown in all of the drawing figures are for illustrative purposes only and form no part of the claimed design.
